JET PUMP
Adiel Y. Dodge, 266 S. Main St., Rockford, Ill.
Filed Sept. 23, 1963, Ser. No. 310,632
13 Claims. (Cl. 103—262)

This invention relates to jet pumps and more particularly to a jet type apparatus for pumping fluids by combined jet and centrifugal action without moving parts.

In my Patents No. 3,131,645 and No. 3,134,338, there is disclosed and claimed jet pump structures involving both jet and centrifugal action and capable of pumping relatively large volumes of fluid with a high degree of efficiency. The present invention relates to improvements on jet pumps as disclosed and claimed in said applications and has for one of its principal objects the provision of a jet pump in which the effect of centrifugal force is utilized to a greater extent and with greater efficiency than heretofore to produce an improved overall pumping efficiency.

According to a feature of the invention, the propellant fluid and the low pressure fluid to be pumped are mixed when both are flowing radially outwardly and are swirling in the same direction. The fluids are preferably mixed in a radially extending mixing chamber which is in open communication with a peripheral vortex chamber having a tangential outlet opening through which the fluid discharges smoothly.

The above and other objects and features of the invention will be more readily apparent from the following description when read in connection with the accompanying drawings, in which:

FIGURE 1 is an axial sectional view from a jet pump embodying the invention;

FIGURE 2 is a section on the broken line 2—2 of FIGURE 1;

FIGURE 3 is a section on the line 3—3 of FIGURE 1;

FIGURE 4 is a view similar to FIGURE 1 of an alternative construction; and

FIGURE 5 is a partial section on the line 5—5 of FIGURE 4.

The jet pump as shown in FIGURE 1 comprises a main casing or housing indicated generally at 10, which is formed at its periphery with a circular or spiral configuration terminating in a tangential outlet conduit 11. Radially within the annular vortex passage as shown at 12, the casing preferably converges to a venturi shaped throat 13. The casing may be made in two parts as shown with its outer surface open and closed by a removal cover 14 to facilitate assembly.

At its inlet side, as seen at the right in FIGURE 1, the casing extends into a cylindrical conduit 15 tapering at its outer end to a reduced seal portion 16 and having an inlet conduit 17 for fluid communicating with one side thereof. A second conduit 18 of smaller size than the conduit 15 extends coaxially through the conduit 15 and is sealed thereagainst at the sealing portion 16. The inner end of the conduit 18 within the housing 10 is flared outwardly to terminate in a radially extending flanged portion 19 which terminates near the inlet end of the venturi section 13. A conical closure 21 is supported over the flared end of the conduit 18 to define therewith an annular flow passage curving outwardly from the conduit 18 and terminating in a radially extending end portion.

The flared portion of the conduit 18 and the closure member 21 are connected by a series of vane elements 22 which are shaped as best seen in FIGURE 2. As there shown, each of the vane elements 22 has a tapered configuration terminating in a flat surface 23 at one end which is at an angle to a radius intersecting the surface. This surface defines with the tail portion of an adjacent vane element a passage or louver directed at an angle to

2

a radius therethrough so that fluid flowing through the passage or louver will be caused to swirl in a clockwise direction as seen in FIGURE 2. By shaping the vanes 22 in the manner illustrated, minimum interference with flow thereover is produced and the outer surface of the vanes presents a generally smooth circular surface interrupted by the louvers around which fluid can swirl with a minimum of turbulence.

A similar set of vanes is secured to the outer face of the conduit portion 19 adjacent to the discharge tips thereof as shown at 24. These vanes, as best seen in FIGURE 3, may be simply flat strips positioned at an angle to radii through the strips in an annular array to cause fluid flowing therewith to swirl. The vanes 22 and 24 are angled in the same direction so that the fluid discharged from the two passages defined by the conduit 18 and by the annular space between conduits 15 and 18 will swirl in the same direction.

In operation of the unit the high pressure propellant fluid, which may be air, steam or any similar desired fluid is supplied through the conduit 17 to the annular space between conduits 15 and 18. This fluid will be directed radially outwardly by the flared portion 19 of the conduit 18 and will flow out between the vanes 24 where it will be caused to swirl rapidly. The low pressure fluid to be aspirated, which again may be air, vapor or the like, is supplied to the inner conduit 18 to flow radially outwardly through the space between the flared end 19 of the conduit and the closure member 21, over the vanes 22. The two fluids will mix at the inlet to the venturi section 13, where they are both swirling in the same direction so that they will mix with each other with a minimum of shock and turbulence. The mixed fluids will continue to swirl as they flow outwardly through the venturi section 13 and the diverging portion of the casing into the vortex chamber 12. The tangential outlet 11 faces into the swirling fluids so that they will flow smoothly from the vortex chamber through the outlet. It will be seen that with this construction both the propellant fluid and the fluid to be aspirated are mixed smoothly while they are both swirling and moving radially outwardly, so that full advantage is taken of both the aspirating effect produced by flow of the propellant fluid and centrifugal force acting on the fluids. The fluids as they continue to swirl flow into the vortex chamber where the rate of swirling tends to reduce so that a portion of the velocity of the fluids is converted to static pressure. It has been found that efficiencies substantially greater than those heretofore obtained with jet pump devices can be achieved in this way and that large volumes of fluid can be moved with the production of relatively high pressure differentials.

FIGURES 4 and 5 illustrate an alternative construction which functions in substantially the same manner as the construction of FIGURES 1 to 3. In this construction a casing or housing 30 is formed in its peripheral portion with a vortex chamber 31 similar to the vortex chamber 12 of FIGURE 1 and having a tangential outlet opening in communication therewith. At one side the chamber is offset as shown at 32 to define a radially extending inlet chamber portion and continues as a cylindrical inlet conduit 33.

The other side of the casing is preferably open for convenience of assembly and is closed by a closure plate 34. The closure plate extends into a cylindrical inlet conduit 35 at the other side of the casing as shown.

The casing is divided by a partition 36 which is secured to the casing wall adjacent to the offset 32 to define therewith a radially outwardly extending flow chamber 37. The partition 36 is formed adjacent its periphery with a series of louvers or openings lying at an angle to the partition to cause the fluid flowing therethrough to swirl.

These louvers or openings can be formed as shown in FIGURE 5 by slitting the partition and bending tabs 38 outwardly therefrom at acute angles thereto.

In order to create an initial swirl of both fluids, each of the conduits 33 and 35 has positioned therein a spiral vane 39. These vanes may be formed of a simple strip of metal helically twisted to cause fluid flowing thereover to swirl. The vanes are so constructed as to cause the fluid entering both of the conduits to swirl in the same direction, which is the same direction in which the louvers 38 tend to create swirl of fluid flowing therefrom.

In use, propellant fluid under high pressure may be admitted to the conduit 33 to flow outwardly through the space 37 and through the louvers 38. This fluid will be caused to swirl initially by the vane 39 in the conduit and the swirling will be fortified by flow of the fluid through the louvers. The low pressure fluid to be aspirated is admitted through the conduit 35 to flow outwardly in the space between the closure 34 and the partition 36. This fluid is swirling in the same direction as the propellant fluid when the two fluids are mixed at the louvers 38 so that the fluids will mix with a minimum of shock and turbulence. In this case also both fluids are flowing radially outwardly when they are mixed so that maximum advantage is taken of both the aspirating effect produced by mixing of the fluids and the centrifugal force acting on the fluids. After mixing the fluids will continue to swirl and will flow radially outwardly into the vortex chamber 31 from which they are discharged through the tangential outlet opening.

While two embodiments of the invention have been shown and described in detail, it will be understood that these are illustrative only and are not to be taken as a definition of the scope of the invention, reference being had for this purpose to the appended claims.

What is claimed is:

1. A jet pump comprising coaxial conduits flaring radially outwardly at one end to define outwardly flaring passages, one of the passages receiving at its smaller end a propellant fluid under relatively high pressure and the other being connected at its smaller end to a source of fluid to be aspirated, means defining a vortex mixing chamber communicating with the larger ends of the passages to receive fluids discharged therefrom, means forming a tangential outlet from the vortex chamber, and means in each of the passages upstream from its larger end to cause the fluids flowing therethrough to swirl in the same direction so that the fluids will mix and enter the vortex chamber while swirling in the same direction and will continue to swirl until they flow out the tangential outlet.

2. A jet pump comprising coaxial conduits defining coaxial passages, one of the passages receiving a propellant fluid under relatively high pressure and the other being connected to a source of fluid to be aspirated, means defining a diffuser chamber connected to and forming a continuation of the outer conduit to receive fluid flowing through both of the passages, means defining a vortex chamber connected to and receiving fluid from the diffuser chamber, means defining a tangential outlet from the vortex chamber, and means upstream from the vortex chamber to cause fluid entering the vortex chamber to swirl in a direction to flow smoothly out the tangential outlet therefrom.

3. A jet pump comprising coaxial conduits defining coaxial passages, one of the passages receiving a propellant fluid under relatively high pressure and the other being connected to a source of fluid to be aspirated, angular sets of vanes in the passages to cause fluid flowing therethrough to swirl in the same direction, means defining a diffuser chamber connected to the outer conduit and flaring smoothly outward therefrom, means defining a vortex chamber connected to the outer end of the diffuser chamber, and means defining a tangential outlet from the

vortex chamber facing toward the swirling fluid to conduct it smoothly from the vortex chamber.

4. A jet pump comprising an annular casing having spaced sides defining an annular mixing and vortex chamber having a peripheral tangential outlet, two conduits defining two passages communicating with the casing adjacent to its axis, one of the passages receiving a propellant fluid under relatively high pressure and the other receiving a fluid to be pumped under a lower pressure, means to direct fluids entering the casing through the passages outwardly in the mixing and vortex chamber and maintaining the fluids separated until they are flowing outwardly, and means in each of the passages to cause the fluids to swirl in the same direction as they enter the mixing and vortex chamber.

5. A jet pump comprising an annular casing having spaced sides defining an annular mixing and vortex chamber having a peripheral tangential outlet, two conduits defining two passages communicating with the casing adjacent to its axis, one of the passages receiving a propellant fluid under relatively high pressure and the other receiving a fluid to be pumped under a lower pressure, an outwardly extending partition member in the casing maintaining the fluids separated until they reach a mixing zone in the mixing chamber radially beyond the conduits, and means in the passages upstream from the mixing zone to cause the fluids flowing therethrough to swirl in the same direction.

6. A jet pump comprising an annular casing having spaced outwardly extending sides closed at their periphery and defining an annular mixing and vortex chamber having a peripheral tangential outlet, a pair of concentric conduits opening into one side of the casing coaxially therewith, the outer conduit being joined to the casing end wall and the end of the inner conduit flaring outwardly to define with the casing separated outwardly extending passages discharging outwardly into the mixing and vortex chamber, and means in the passages upstream from the discharge ends thereof to cause fluids flowing therethrough to swirl in the same direction.

7. A jet pump comprising an annular casing having spaced outwardly extending sides closed at their periphery and defining an annular mixing and vortex chamber having a peripheral tangential outlet, a pair of concentric conduits opening into one side of the casing coaxially therewith, the outer conduit being joined to the casing end wall and the end of the inner conduit flaring outwardly to define with the casing separated outwardly extending passages discharging outwardly into the mixing and vortex chamber, and angular vanes in the passages at their discharge ends to cause the fluid discharging from the passages to swirl in the same direction.

8. The jet pump of claim 6 in which the sides of the casing converge toward each other outwardly of the discharge ends of the passages to provide a narrow high velocity zone and then gradually flare toward the outer vortex portion of the casing.

9. A jet pump comprising an annular casing having spaced outwardly extending sides closed at their periphery and defining an annular mixing and vortex chamber having a tangential peripheral outlet, a pair of conduits defining passages opening axially into the casing at opposite sides thereof, a radially extending partition in the casing between the passage openings, the partition being formed with openings therethrough to permit mixing of the fluids radially outward from the passages, and means in the passages upstream from the last named openings to cause fluids flowing through the passages to swirl in the same direction.

10. The jet pump of claim 9 in which the openings in the partition are defined by louvers tending to cause the fluid flowing therethrough to continue to swirl in the direction in which it is caused to swirl by said last named means

11. In a jet actuated pump, the combination of a fixed

spiral vortex housing, means to supply high pressure propellant fluid and low pressure fluid to the housing at points adjacent to the axis of the housing to outwardly therein, means defining a tangential outlet at the periphery of housing, means to cause the high pressure fluid to swirl in said housing comprising a multiplicity of vanes spaced outward from the point of entry of the high pressure fluid delivering fluid therethrough in a radially outward generally tangential direction in the manner of jets to cause fluid to swirl in said vortex housing thereby to cause a pumping action to draw in low pressure fluid and discharge it at higher pressure.

12. In a jet actuated pump, a fixed spiral vortex housing, means to supply high pressure propellant fluid and low pressure fluid to be pumped to the central part of the housing in radially outwardly extending paths, vanes in

said paths to cause the fluid flowing therethrough to swirl as it enters the housing, and a tangential outlet conduit opening into the outer part of the housing.

13. The pump of claim 12 in which the housing is formed with an annular area of venturi section radially outward from the discharge ends of said paths and adjacent thereto.
